BOTTLE CARRIER

Jean F. De Villard, Chicago, Ill., assignor, by
mesne assignments, to Charles W. Stiefel, Jr.,
Chicago, Ill.

Application November 16, 1940, Serial No. 365,996

1 Claim. (Cl. 224—45)

1

This invention relates to a bottle carrier of the type disclosed in my copending application, Serial No. 324,980, filed March 20, 1940, which involves a stamped sheet of blank cardboard, or cotton fibre with side braces cut therefrom.

These stamped blanks are sold and stored in sheet form and when it is desired to use one, it is folded into shape and the cut braces are manually pulled out of their slots and directed outwardly. This operation involves time and labor; then sometimes the braces tend to spring back into their slots. Further, such carriers have not been sufficiently reinforced in the past with the result that in carelessly handling the same when loaded, they might fracture and cause the bottle to drop upon the feet of the person carrying the load, and a damage suit would result.

My new form of bottle carrier constitutes a notable improvement upon the prior carriers in that the braces are cut and creased in such a manner that they automatically rise and assume proper positions when the blank is folded into a bottle carrier, thereby eliminating the usual necessary manual operation.

Further the blank is reinforced in such a manner that it is not likely to tear and fracture and drop the contents when used in transporting a load.

In addition, the carrier is provided with interlocking parts to maintain the same in carrier form after the blank has been folded up.

Further the sides of the carrier are provided with separate apertures which may be provided with flaps for receiving the necks of the bottles.

With these and other features in view, the invention comprises the novel structure and combination of parts hereinafter described and more particularly pointed out and defined in the appended claim.

In the accompanying drawings which illustrate a preferred form of this invention and in which similar reference numerals refer to similar features in the different views:

Fig. 1 is a top plan view of a bottle carrier involving this invention;

Fig. 2 is a sectional view taken upon the line II—II of Fig. 1 looking in the direction of the arrows and showing bottles in dotted lines;

Fig. 3 is a sectional view taken upon the line III—III of Fig. 2 looking in the direction of the arrows;

Fig. 4 is a fragmentary sectional view taken upon the line IV—IV of Fig. 2;

Fig. 5 is a fragmentary sectional view taken upon the line V—V of Fig. 3;

2

Fig. 6 is a fragmentary sectional view taken upon the line VI—VI of Fig. 3;

Fig. 7 is a plan view of the blank cut and creased and ready to be folded up to form the carrier shown in Figs. 1 and 2; and

Fig. 8 is a sectional view through the blank illustrating in diagrammatic form the automatic elevation of the braces.

In referring now to the drawings which illustrate a preferred form of this invention, it will be noted with reference to Fig. 7 that the carrier is formed from a substantially rectangular blank 1 which may be made of any suitable desired length in accordance with the height of the bottles it is designed to support and which may be made of any suitable material such as cotton fibre.

Along each side of the blank 1 there is a reinforcing lip or flange 2 which is marked off from the main body of the blank by crease lines 3. These reinforcing flanges terminate in bevelled ends 4 spaced inwardly short distances from the ends of the blank. The lips or flanges 2 are severed at the points 5 for a purpose that will later appear and they are provided with the V creases 6 a short distance beyond the cuts 5 for folding purposes during assembly.

The bottom portion or base 7 of the carrier is defined upon the blank 1 as existing between the crease lines 8. Spaced inwardly a short distance from each crease line 3, there is a cut or incision 9 which extends across the base 7 of the blank and a short distance into the side portions 10. From the ends of each incision 9, there extend crease lines 11 which slope toward each other at angles of about 45° to the incision 9. These crease lines 11 extend from the incisions 9 to the crease line 3. It will be noted that the lips 2 are also creased in alignment with the crease lines 8 as indicated at 12. From the crease lines 12, there extend crease lines 13 which slope slightly toward each other as they pass over the braces 14 which, it will be noted, are defined by the lines 3, 9 and 11.

These sloping crease lines 13, it will be noted, are inwardly offset from the bottom crease lines 8, and constitute offset breakers that are mainly instrumental in connection with the crease lines 11 to cause the braces 14 to automatically rise upon crease lines 3 as hinges when the blank is folded into a carrier.

At the upper ends of the parts 10 of the blank 1 that serve as the lower side portions of the carrier, there are spaced partially cut out strips 15. These strips 15 are so cut out from the main

body of the blank, that their sides are severed from the main body of the blank by the irregular cuts 16 and 17 while the upper portions 18 and the lower portions 19 are not severed from the blank. The strips 15 are thus hinged at their upper and lower ends.

Between each pair of strips or connectors 15 and at the lower ends thereof there is an incision 20 which causes that portion between the strips 15 to become flaps. The flap at one end is designated 21, while the flap at the other end is designated 21a. The flap 21 is formed with a locking slot 22 for receiving a teat 21b on the flap 21a to fasten the sides together.

Flaps 23 are also formed adjacent the outer edges of the connectors 15 by incisions 24 and 25. The incisions 24 are in alignment with the incisions 20 while the incisions 25 extend parallel to the crease lines 3 and spaced a short distance inwardly therefrom. The incisions 25 extend downwardly a short distance below the incision 24 and converging crease lines 26 extend therefrom to the crease lines 3 for folding purposes. One of the crease lines 26 upon each edge of the blank extends from the lower end of the incision 25.

When the blank is folded up into carrier form as shown in Figs. 1 and 2, the flaps 21 and 23 form three apertures through which the bottles are adapted to be inserted into the container. These apertures are clearly shown in Fig. 1 and are designated 27, 28, and 29; the carrier being designed in the present instance to carry six bottles, three on each side. The curved lobes 15a on the strips or connectors 15 serve as bendable 30 filler members for bearing against the upper portions of the bottles. Of course, when the blank is folded into carrier form, the flaps 21, 21a and 23 will move inwardly out of the plane of the blank and assume vertical positions as shown in Figs. 1 and 2. In this operation, the teat 21b can be inserted in the locking slot 22 to fasten the upper neck parts of the carrier together.

For further fastening the upper parts of the carrier together, the handle aperture 30 is adapted to receive a locking flap or tongue 31 cut from the other side of the carrier as is well known in the art. For further security, a second slot 32 is formed beneath the slot 30 for receiving a tongue 33 cut from the opposite side of the carrier. Thus the upper parts of the carrier are adapted to be securely fastened together.

To complete the blank so that it is ready for use, the lips 2 are folded over upon the back or outer edge portions of the blank and portions glued thereto. It might be mentioned that the portions of the lips 2 above or beyond the upper creases 6 are secured or glued to the reverse side of the blank, and the parts between the incisions 5 and the creases 12 are also glued or secured to the reverse side of the blank. The portions of the lips 2 between the incisions 5 and creases 6 are free. It will be noted that cuts 34 extend from the incisions 25 to the apices of the creases 6 whereby the portions 35 which are partially cut from the blank by the incisions 25 and 34 cooperate with the adjacent part of the lip 2 to form a connection between the side portions 10 and the handle portions of the blank. At the same time, these connecting strips 35 form the outer walls of the bottle apertures 27 and 29, as shown in Fig. 1. Due to the cuts 34 and the creases 26, the flaps 35 will fold upright when in use, as shown in Fig. 1.

In forming the blank into a carrier, the side

portions are folded up about the crease lines 8 as axes, the teat 21b is then inserted in the slot 22 and the tongues 31 and 33 are inserted respectively through the slots 30 and 32 whereby the parts will take the positions shown in Figs. 1 to 3, the connecting strips 15 and 35 assuming substantially a horizontal position.

It is an important feature of this invention that when the side portions 10 turn or bend upwardly with reference to the crease lines 8 as shown in Fig. 8, the braces 14 will be automatically elevated into substantially vertical positions as shown in Fig. 3. In their elevating movements, the braces 14 will turn upon the crease or border lines 3 as axes. For it will be evident that as the lower side portions 10 are folded up, the braces 14 cannot fold upon the lines 8 but there will be a tendency to shorten them by the pressure at each end. Ordinarily this pressure would cause the same to bow in one or the other direction, but due to the offset breaker creases 13, the portion between such creases 13 will move toward their end of the carrier.

To make it a little plainer, it will be evident that as the crease lines 11 are brought closer together as the sides of the carrier are folded up, the pressure exerted against the ends of the braces 14 will cause the braces 14 to spring up and outwardly due to the offset crease lines 13. In other words, the braces 14 respond to the movements of the side portions 10 with respect to the bottom 1. When the sides are folded up the braces 14 pop up and outwardly and they recede when the sides are lowered. Thus, the movement of the sides controls the braces 14 and this automatic action of the braces 14 eliminates the tedious manual operations that were heretofore required in such carriers.

It will also be evident that the reinforcing lip or flange 2 greatly increases the strength of the carrier. The free portions of the flanges 2 contiguous to or under the braces 14 also form the support for such braces and allow the same to be brought clear to the outer side edges of the carrier; and at the same time, they prevent the flanges 14 from flipping downward and assist in the upward flipping action thereof.

When the carrier is ready for loading, the bottles can be placed in the pockets one at a time or several can be simultaneously placed therein, so the loading can be expedited over certain carriers now in use.

I am aware that numerous changes may be made and various details of construction may be varied without departing from the principles of this invention, and I do not propose limiting the patent granted otherwise than necessitated by the prior art and appended claim.

I claim as my invention:

60 In a bottle carrier formed from a blank made from cardboard or like material to afford, when erected, a bottom wall, side walls joined along fold lines to opposite side edges of said bottom wall, bottle receiving sections joined along fold lines to the upper edges of the respective side walls, a handle section joined along fold lines to the other edges of the two bottle receiving sections so as to project upwardly therefrom, bottle retaining end walls formed from the material of said bottom wall adjacent to the last mentioned fold lines, and bellows fold means joining opposite ends of said bottle retaining walls to the opposite side walls to maintain said retaining walls in upright positions when said carrier is erected and to effect erecting movement of said

retaining end walls when in the course of erection of said carrier said side walls are bent upwardly with relation to said bottom wall, reinforcing flaps joined along fold lines to the opposite end edges of said side walls and to said retaining end walls, the flaps joined to said side walls being folded along said fold lines to lie flat

against the outer faces of the walls to which they are joined, and the flaps joined to said end walls affording supporting strips substantially in the plane of said bottom wall and supported in part by said retaining end walls when said retaining end walls are in their upright positions.

JEAN F. DE VILLARD.
